(57) **CLAIM**

The ornamental design for a pan for a loadable weight sled, as shown and described.

DESCRIPTION

FIG. 1 is a top, front, left perspective view of a pan for a loadable weight sled showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even length broken lines depicting the remainder of the pan for a loadable weight sled form no part of the claimed design.

1 Claim, 7 Drawing Sheets
